(57) **CLAIM**

The ornamental design for an air fryer, as shown and described.

DESCRIPTION

FIG. 1 is a perspective view of an air fryer in accordance with the present disclosure;

FIG. 2 is a view of the air fryer shown in FIG. 1 from the front;

FIG. 3 is a view of the air fryer shown in FIG. 1 from the rear;

FIG. 4 is a view of the air fryer shown in FIG. 1 from the left;

FIG. 5 is a view of the air fryer shown in FIG. 1 from the right;

FIG. 6 is a view of the air fryer shown in FIG. 1 from the top;

FIG. 7 is a view of the air fryer shown in FIG. 1 from the bottom;

FIG. 8 is a perspective view of an air fryer in accordance with the present disclosure;

FIG. 9 is a view of the air fryer shown in FIG. 8 from the front;

FIG. 10 is a view of the air fryer shown in FIG. 8 from the rear;

FIG. 11 is a view of the air fryer shown in FIG. 8 from the left;

FIG. 12 is a view of the air fryer shown in FIG. 8 from the right;

FIG. 13 is a view of the air fryer shown in FIG. 8 from the top; and,

FIG. 14 is a view of the air fryer shown in FIG. 8 from the bottom.
